COMBINED LID HOLDER AND DRIP CATCHER

Emily Silverman, 3927 Sherwin Ave., Lincolnwood, Ill.

Filed Jan. 17, 1963, Ser. No. 73,220

Term of patent 7 years

(Cl. D44—26)

FIG. 1 is a perspective view of the combined lid holder and drip catcher embodying my new design;

FIG. 2 is a top plan view thereof;

FIG. 3 is a side elevational view as seen from the bottom of FIG. 2;

FIG. 4 is a front elevational view as seen from the left-hand side in FIGS. 2 and 3; and

FIG. 5 is a rear elevational view as seen from the right-hand side in FIG. 3.

I claim:

The ornamental design for a combined lid holder and drip catcher, substantially as shown.
